APPARATUS FOR EMBALMING

Clyde L. Spurgeon, Salem, W. Va.

Application March 8, 1949, Serial No. 80,233

8 Claims. (Cl. 27—21)

1

This invention relates to a device for use by undertakers during the preparation of a corpse for burial. More particularly, this invention relates to a method and apparatus for insuring that the corpse will be properly positioned in the coffin or casket.

In the art of embalming, one of the primary objects is properly to position the body in as natural and attractive position as possible. To this end, certain members of the body, notably the arms, should be carefully held in position until the body has assumed rigidity.

The primary object of this invention is to provide an improved method and apparatus for supporting and positioning the arms of the body being embalmed so that the arms are properly positioned along the sides of the body and across the front thereof, if so desired.

Another object is the provision of a method and apparatus for positioning the arms of a corpse being embalmed such that the support provided by the apparatus can readily be removed without disturbing the arms after they have assumed their final position.

Another object is the provision of a device for use by embalmers for supporting in positioning engagement the arms of the bodies being embalmed which is flexible so as to be adjustable for body and arm dimensions of all sizes.

A still further object is the provision of a device of the character described which is simple to use and which provides positive support for the said arms.

Still another object is the provision of a relatively inexpensive device for the purposes set forth.

It is also an object of this invention to provide an instrument which can readily be folded for storage in a minimum amount of space or for being shipped.

It is also an object to provide a collapsible instrument of the character described which, while being collapsible for shipping or storage, is nevertheless rigid when in use.

These and other objects and advantages will become more apparent upon reference to the following description taken in connection with the accompanying drawings in which:

Figures 1 and 2 are plan and side views respectively of a device according to this invention showing the manner of use thereof.

Figures 3 and 4 are plan and side views respectively of the device but are drawn at a larger scale and illustrating also a somewhat modified arrangement for permitting collapsing of the device when not in use;

2

Figure 5 is a perspective view showing the telescopic arrangement of the frame of the device;

Figure 6 is a cross-section through the telescoping frame part and is indicated by the line 5 6—6 on Figure 3;

Figure 7 is a view indicated by the line 7—7 on Figure 3 showing the construction of the upper arm supporting element; and

Figure 8 is a perspective view showing the construction by means of which the instrument can be collapsed for storage or shipping.

Referring to the drawings somewhat more in detail, there is indicated in dot-dash outline at 10 in Figures 1 and 2, a corpse which is being embalmed. The device of this invention is generally indicated in these figures at 12, and it will be seen to comprise a frame part 14 adapted for extending transversely of the corpse and therebeneath and brackets or shaped rods 16 at opposite ends of the frame part 14 and extending generally longitudinally of the corpse.

The brackets 16 have upstanding end parts thereon extending generally perpendicularly. The upper of the upstanding end parts are indicated at 18 and are laterally offset by the brackets 16 being bent outwardly adjacent thereto. The brackets 16 may be formed of any suitably strong material and may be of any cross-sectional shape but are preferably cylindrical, as shown.

The aforementioned upstanding end parts 18 have adjustably mounted thereon the arcuate arm engaging elements 20 which, as will be seen from the shape thereof and from the illustrations in Figures 1 and 2, are adapted for engaging the outer and under parts of the arms between the shoulder and elbow. These elements thus provide support for the arms for retaining them in a predetermined elevated position and also urge the arms toward the body. It will be evident that it is desirable for the elements 20 to be vertically adjustable on their associated end parts 18, as well as angularly adjustable. This is accomplished by supporting the elements 20 on said end parts by means of the collar arrangement at 22 and the adjustable clamping screw 24, best illustrated in Figure 7.

It will also be evident that it is desirable for the elements 20 to be adjustable laterally relative to each other to accommodate for different widths of bodies. To this end the frame part 14 consists of a tubular or sleeve part 26 secured to one of the brackets 16 as by the bolts 28 and a rod or bar part 30 secured to the other bracket 16 as by the bolts 32. This manner of joining the brackets 16 to the frame part is shown in

Figures 1 and 2 while a collapsible type connection is shown in Figures 3 and 4. In other respects Figures 1, 2, 3, and 4 are alike. As will be seen in Figures 5 and 6, the sleeve part 26 loosely receives the bar 30 so the instrument can be adjusted along the length of the frame part 14 and thus vary the lateral spacing of the elements 20. For the purpose of releasably retaining the parts 26 and 30 of the frame 14 in a plurality of positions of adjustment, there is an upstanding finger or projection 34 on the bottom wall of the sleeve part 26 and a plurality of axially spaced apertures or recesses 36 opening upwardly in the bottom of the rod or bar part 30 for receiving the said projection.

The bar 30 can be released from engagement with the projection 34 by lifting the said bar, and in this position, the bar and sleeve can be adjusted as to the degree of their telescopic engagement or taken completely apart. When the bar 30 is released or occupies a position shown in Figures 1 and 2, it is interlocked with the sleeve 26, and this predetermines the spacing of the elements 20.

At their lower ends, the brackets 16 have their upstanding end parts 38 and adjustably mounted on these end parts are other arm engaging elements 40. The elements 40 are of the shape of inverted U's and are adapted for fitting over the arms below the elbows, preferably adjacent the wrists. Inasmuch as it is not necessary for the elements 40 to provide any lifting support for the arms, they are provided with bracket members or clips 42 extending outwardly therefrom which have therein a plurality of apertures 44 for slidably receiving the upstanding parts 38 of the brackets 16. The plurality of apertures in the members 42 permit adjustment of the elements 40 toward and away from the upstanding end parts 38 as well as movable vertically therewith so that they can be fitted over the said forearms in the proper manner.

In practice, it has been found that the spacing between the upstanding parts 18 should be variable from about sixteen inches to twenty-five inches, and that the distance between the two upstanding end parts on each bracket should be somewhere between eleven and twelve inches. The lateral adjustability or extensibility of the frame 14 is made in steps of about one inch each.

Operation

In operation, one of the brackets 16 and its associated frame part is placed adjacent the body with the frame part extending therebeneath. The other bracket 16 and its frame part is placed on the other side of the body and the two frame parts placed in telescopic engagement. The instrument can then be adjusted to the proper width by raising the bracket end of the bar 30 of the frame and shifting it into tube part 26 of the frame. After the instrument is adjusted as to width and the bar 30 is released, it will lock into position by engagement of the projection 34 with the recesses or apertures 36 nearest thereto. Thereafter, the elements 20 are adjusted on the end parts 18 to support the arms of the body in the desired position.

Thereafter, the elements 40 are placed over the forearms for retaining them in the proper position. At this time the arms of the body will be held in the desired position, and this materially assists in properly positioning a body in the coffin.

Thereafter, the instrument can be removed,

and it is to be noted that this can be accomplished without disturbing the positions of the arms in any way whatsoever. To remove the instrument the elements 40 are removed by lifting them vertically from the upstanding end parts 38 of the brackets 16. The instrument is then extended by lifting one end of the bar 30 and pulling the two parts of the instrument apart. It will be observed that due to the fact that the elements 20 engage only the outer and lower parts of the arms above the elbows, the instrument can be removed without in any way disturbing the arms.

It will be seen that the method and apparatus which I have invented for positioning and holding the arms of a body during the process of embalming is quite effective and leads to superior results in that the arms are firmly held in position due to the arm supporting elements being rigidly connected by the instrument frame, but that the instrument can readily be removed from the body without disturbing the arms. Further, the flexibility of the frame and the adjustable supports for the arm supporting elements permits easy and exact adjustment of the instrument to all sizes of bodies and for accomplishment of all desired poses of the arms.

Figure 8 is a fragmentary view showing in perspective the manner in which the brackets or rods 16 are connected with the parts 26 and 30 in Figures 3 and 4 so the instrument can be folded for storage or shipping. In these views the end of the bar 30, or the sleeve 26, as the case may be, is bent around the rod 16, thereby to provide a pivotal support therefor. The bar or sleeve is slotted at 50 for receiving a stud 52 which extends into the bar 16. The length of the slot 50 is such that stud 52 occupies the position shown in full lines when the instrument is in use and the position indicated in dot-dash outline when the instrument is folded for shipping or storage.

It will be evident that while this arrangement permits the instrument to be readily collapsed, it still provides for maintaining the arm engaging elements in rigid relationship when the instrument is in use. It will also be evident that the particular arrangement shown for providing for the pivotal connection of the rods 16 to the parts 30 and 26 is only exemplary of many other arrangements that could be made to obtain the collapsibility of the instrument.

It will be understood that this invention is susceptible to modification in order to adapt it to different usages and conditions, and, accordingly, it is desired to comprehend such modifications within this invention as may fall within the scope of the appended claims.

I claim:

1. In a device of the character described; a laterally extensible frame, a longitudinally extending bracket at each end of the frame having spaced upstanding end parts integral therewith, arcuate arm engaging elements on the said end parts of said brackets, the element at one end of each said bracket opening inwardly and upwardly for engagement with the outside and lower parts of the arms above the elbow, said last named elements being adjustable on their associated end parts, angularly relative thereto and also along the length thereof, the others of said elements opening downwardly for fitting over the arms below the elbow, said others of said elements being adjustable on the other end parts of said brackets angularly relative thereto, along the

length thereof and toward and away from the said end parts.

2. In a device of the character described; a telescoping frame adapted for being positioned transversely beneath a corpse at about the waist thereof, means for retaining said frame in a plurality of telescopic positions so the ends thereof are adjacent the sides of said corpse, brackets on the ends of the frame extending generally longitudinally of the corpse and having upstanding end parts, an arcuate arm engaging element on the upstanding end part at the head end of each of said brackets, means detachably clamping the said elements on said upstanding parts for angular adjustment relative thereto and for adjustment along the length of said upstanding parts, other arcuate arm engaging elements adapted for being supported on the upstanding parts at the other ends of said brackets, said other elements having clips secured thereto and said clips each having a plurality of apertures therein for receiving the upstanding part at the said other ends of said brackets so said other elements are adjustable along the length of the supporting end parts of the said brackets, angularly relative thereto, and toward and away from the said end parts.

3. In combination in a device of the character described; a pair of generally parallel and laterally spaced brackets, arm engaging elements adjustably supported by said brackets so as to provide support for the arms of a corpse above and below the elbows thereof, a bar secured to one bracket and extending toward the other bracket, a sleeve secured to the said other bracket and telescopically receiving said bar, and latch means for retaining said bar and sleeve in a plurality of positions of telescopic adjustment.

4. In combination in a device of the character described; a pair of generally parallel laterally spaced brackets, arm engaging elements adjustably supported by said brackets so as to provide support for the arms of a corpse above and below the elbows thereof, a bar secured to one of said brackets between its ends and extending toward the other of said brackets, a sleeve secured to the said other of said brackets and loosely telescopically receiving said bar, a projection upstanding from the bottom wall of said sleeve, and a plurality of spaced apertures opening into said bar from the bottom part thereof for receiving said projection.

5. A device for positioning the arms of a corpse being embalmed comprising; a frame member for extending generally transversely of the corpse, a bracket on each end of the frame member extending generally longitudinally of the corpse, a first pair of elements on said brackets adapted for supporting engagement with the arms of the

corpse above the elbows thereof, and a second pair of elements on said brackets adapted for supporting engagement with the said arms below the elbows thereof, said brackets being pivotally connected with said member for permitting the device to be collapsed for storage or shipment.

6. In a device of the character described; an extensible frame, a bracket at each end of the frame having upstanding end parts, and arcuate arm engaging elements on the said end parts of said brackets, the elements at one end of said brackets opening inwardly and upwardly for engaging the outside and lower parts of the arm above the elbow, and the other elements opening downwardly for fitting over the arm below the elbow, said brackets being pivotally connected with the ends of said frame for collapsing of the device for shipping or storage.

7. In combination in a device of the character described; a pair of generally parallel and laterally spaced rod-like brackets, arm engaging elements adjustably supported by said brackets so as to provide support for the arms of a corpse above and below the elbows thereof, a bar secured to one bracket and extending toward the other bracket, a sleeve secured to the said other bracket and telescopically receiving said bar, and latch means for retaining said bar and sleeve in a plurality of positions of telescopic adjustment, said brackets being pivotally secured to said bar and sleeve for permitting collapsing of said device.

8. In combination in a device of the character described; a pair of generally parallel and laterally spaced rod-like brackets, arm engaging elements adjustably supported by said brackets, a transverse frame extending between said brackets and connected thereto adjacent their intermediate portions, means pivotally connecting said brackets with the ends of said frame for pivotal movement of the brackets in a plane substantially perpendicular to their axes, and means for limiting the pivoting movement of said brackets in at least one direction.
